COMBINED ROTISSERIE OVEN AND FOOD WARMING CABINET

Robert G. Wilson, 643 E. Faris Foad, Greenville, S.C.

Filed Apr. 2, 1962, Ser. No. 69,527

Term of patent 14 years

(Cl. D81—10)

Fig. 1.

Fig. 2.

FIGURE 1 is a perspective view of a combined rotisserie oven and food warming cabinet embodying my new design, and

FIGURE 2 is a perspective view of the combined rotisserie oven and food warming cabinet taken from the rear of FIGURE 1 further illustrating my new design.

I claim:

The ornamental design for a combined rotisserie oven and food warming cabinet, substantially as shown.
